UNITED STATES PATENT OFFICE.

WILLIAM G. SEATON, OF KNOXVILLE, TENNESSEE.

AUTOMATIC DRAFT-REGULATOR.

1,372,563.

Specification of Letters Patent. Patented Mar. 22, 1921.

Application filed September 11, 1917. Serial No. 190,831.

To all whom it may concern:

Be it known that I, WILLIAM G. SEATON, a citizen of the United States, residing at Knoxville, in the county of Knox and State 5 of Tennessee, have invented new and useful Improvements in Automatic Draft-Regulators, of which the following is a specification.

This invention relates to an automatic 10 draft control and spark remover primarily adapted for use in connection with locomotives, but also adaptable to boilers for other classes of engines.

It is an object of the invention to produce 15 a combined draft control and spark remover for the boilers of locomotives or like engines, which shall be automatic in action, easily installed, cheap in construction, and thoroughly efficient in operation.

20 With this object in view, and others which will appear as the nature of the invention is more fully understood, the invention resides in the construction, combination, and operative arrangement of parts set forth in the 25 following description and falling within the scope of the appended claim.

In the drawings,

Figure 1 is a side elevation of the improvement, the locomotive being indicated 30 by the dotted lines.

Fig. 2 is an approximately central vertical longitudinal sectional view through the motor cylinder.

Fig. 3 is a fragmentary perspective view 35 looking toward the bottom of the smoke box.

Fig. 4 is a front elevation partly in section.

Fig. 5 is a vertical longitudinal sectional view through the blow-out valve.

40 Fig. 6 is a detail side elevation illustrating the cap or valve for the air inlet in its partly open position.

To the dome 11 for the boiler of a locomotive 10, I connect a pop valve 12, illustrated 45 in detail in Fig. 5 of the drawings. This valve comprises an outer casing 13 having a removable threaded cap 14 and an inner cylindrical member 15 which is provided with a seat for the spring pressed valve 16, the said valve being disposed directly above a steam pipe 17 from the dome 11. The outer casing 13, upon one of its sides is provided with an opening surrounded by a boss and within the said opening is screwed a

55 pipe 18 leading, through a series of connect- ed pipes 20—20 to a closed cylindrical cas- ing 21, located below and secured at a con- venient point to the smoke box 22 at the outer end of the boiler. In the casing 21 is a piston 23 having a stem 24 that passes 60 through a suitable packing box at the front end of the cylinder. Surrounding the stem 24 is a helical spring 25 exerting a pressure between the piston 23 and the outer end of the cylinder to normally force the piston 65 toward the rear end of the cylinder, and toward the pipe 20 which connects with the said rear end of the cylinder. The cylinder 21, upon its under face, and adjacent its ends, is provided with restricted openings, 70 receiving the stems of cocks 25' and 26 re- spectively, the cock 25' being at all times partly open, and forming a bleed port at the rear end of the cylinder. Integrally formed with the cylinder 21, upon the top thereof 75 is a box-like chamber 27 having its outer wall provided with an inlet opening nor- mally closed by a removable threaded plug 28. The chamber, at its said upper wall is provided with an outlet drain pipe 30. The 80 numeral 30' designates the port between the receptacle 27 and the cylinder 21. The cyl- inder is designed to receive a fluid prefer- ably a mixture of oil and water, which, in 85 Fig. 2 of the drawings, is indicated by the numeral 31, the said fluid serving as a buffer for the piston 23.

Formed upon or connected to the under face of the cylinder 21 and extending out- 90 wardly of the said cylinder, that is, toward the front end of the cylinder 21 is the arm 32 of a bracket member 33. On this bracket 33 is secured the guide frame 34 for a cross head 35 to which is connected the project- 95 ing end of the piston rod 24. Pivoted con- nected with the cross head 35 is a link 36.

The bottom wall of the smoke box, adja- 100 cent the outer end thereof, is provided with an opening 37, and surrounding this open- ing is the flange 38 of a depending pipe member 40. The flange is riveted or other- wise secured to the bottom of the smoke box. The pipe, at the lower end thereof, is formed with a lateral extension 41, the ends there- 105 of being closed by removable heads 42. The pipes 40 and 41 provide a substantially in- verted T-shaped member, and the horizon- tal element 41 thereof, at the opposite sides

of the vertical member 40, is provided with round openings which are surrounded by flanges 43. The openings provide air inlets for the inverted T-shaped pipe and these inlets are normally closed by flanged hinged doors or valves 44. Pivotally connected to each of the flanged caps or valves 44 is a rod 45. Each of the rods is preferably in the nature of an adjustable element, 10 and in reality comprise two rods having their confronting ends oppositely threaded and the said ends engaged by a turn buckle 46.

The vertical member 40 of the air inlet pipe is provided with alining openings passing through the sides thereof, the said openings being surrounding by bosses 47 and provide bearings for a shaft 48. The shaft has at one of its ends an angular arm 49 which is preferably bifurcated and pivotally connected with one of the rods 45. The second end of the shaft 48 is connected to the center of an arm 50. This arm has one of its ends pivotally connected with the second rod 45, and its opposite end pivoted to the link 36.

Arranged over the opening 37 in the smoke box is a cross sectionally U-shaped hood or shield 51, the same having its edges 30 provided with depending legs 52 having offset feet 53 which are secured to the lower wall of the smoke box 22. As illustrated in Fig. 1 of the drawings, the upper wall of the hood 51 is arranged at an inclination, 35 so that the wider end of the said hood is disposed adjacent the outer end of the smoke box, and this end, at the upper portion thereof, is formed with an outwardly flared lip 54. In some instances the hood 52 may 40 be dispensed with.

The spring pressed pop or blow-off valve 12 is operated by an excessive pressure of steam in the boiler which pressure, however, is not great enough to unseat the regular pop or blow-off valve connected with the dome 11. When the valve 12 is operated the steam will be directed through the pipes 18 and 20 against the piston 23, moving the piston longitudinally of the cylinder 21 45 against the pressure of the spring 25 and the influence of the fluid 31 in the cylinder, causing the piston rod to move the cross head 35 outwardly or toward the end of the smoke box, and consequently, causing the link 36 to turn the shaft 48 to operate the rods 45 and open the valves or caps 44 of the inlets to the air pipe 40, permitting fresh air to flow through the said pipe, and to create a direct vertical draft in the smoke box through the smoke stack, thus relieving a direct horizontal draft through the smoke tubes of the boiler. In addition to creating the draft and relieving the steam pressure, the air collects and forces the cinders and

other products of combustion from the 65 smoke box through the smoke stack. The operation of the device, it will be noted, is automatic, the construction is comparatively simple and the device not only obviates the necessity of removing the cinders or other 70 products of combustion by hand, but economizes the use of steam and water in the boiler.

The longitudinal pipe member 20 may be extended to the rear of the boiler as illustrated in Fig. 1 of the drawings, and connected by a T to a valve pipe 55 which in turn is connected to a branch pipe that communicates with the boiler, the T being provided with a cock 56 which is partly open. 80 This partly opened cock provides a bleed for the pipe 55 to the pipe extension 20 and in connection with the cock 25' permits of the return of the piston 23 to its initial position after the exhaust pressure has been relieved. The valve 57 of the pipe 55 is arranged in close proximity to the engineer by whom it may be operated. Thus the device may be operated manually if desired.

The cock 26 is employed as a drain for the 90 fluid 31 so that the fluid will not be permitted to freeze in the cylinder in cold weather or when other conditions arise and it is found necessary to remove the fluid from the same. Should too great a quantity of the fluid 31 95 be arranged in the receptacle 27, the same will find an outlet through the pipe 30.

Having thus described the invention, what I claim is:

In an automatic draft regulator for 100 locomotive engines, the combination with a casing secured to and communicating with the steam dome of the engine boiler; a spring influenced puppet valve in the casing normally closing the casing to the dome, and a 105 pipe leading from said casing; of a cylinder secured to the locomotive adjacent to the front end thereof, the pipe from the casing connected with the rear end of the cylinder, the cylinder having a fluid containing chamber communicating with the forward end thereof, said cylinder having a bleed cock adjacent each of its ends, the bleed cock at the rear end of the cylinder being normally partly open, a piston in the 110 cylinder, a piston rod therefor passing through the front end of the cylinder, a spring surrounding the rod and exerting a pressure to move the piston toward the rear end of the cylinder, an air inlet pipe connected to and communicating with the smoke box of the locomotive, a hood in the smoke box disposed over the pipe, a hinged door for the pipe controlling the admission of atmospheric air therethrough, means connected to the door and to the piston rod for swinging the door to open position to admit atmospheric air through the pipe and 115 120 125

into the smoke box when the piston is influenced by steam from the casing of the puppet valve when an excess steam pressure occurs in the dome, the piston, in such movement compressing the spring and forcing part of the fluid from the cylinder into the fluid chamber, and the spring designed to move the piston to its initial position to

force the steam through the open bleed cock, when the excessive steam pressure in the dome is relieved, and in so doing to return the door of the air inlet pipe to closed position.

In testimony whereof I affix my signature.

WILLIAM G. SEATON.
